UNITED STATES PATENT OFFICE.

THOMAS W. GLINES, OF WASECA, MINNESOTA.

INDESTRUCTIBLE WICK.

1,207,160.

Specification of Letters Patent.

Patented Dec. 5, 1916.

Application filed May 25, 1916. Serial No. 99,768.

To all whom it may concern:

Be it known that I, THOMAS W. GLINES, a citizen of the United States, residing at Waseca, in the county of Waseca and State 5 of Minnesota, have invented certain new and useful Improvements in Indestructible Wicks; and I do hereby declare the following to be a full, clear, and exact description of the invention, such as will enable others 10 skilled in the art to which it appertains to make and use the same.

My invention has for its object to provide a highly efficient indestructible wick for burning combustible liquids, but more particularly, has for its object the provision of such a wick of large size, usually in tubular form, for use in connection with heating and cooking stoves burning kerosene, or other heavy hydrocarbon liquid. By an indestructible wick, I mean a wick that will not be 20 burned up in use.

The present invention is in the nature of an improvement on or modification of the wick disclosed and broadly claimed in my prior Patent 1,178,850, of date, April 11, 25 1916, entitled "Non-combustible wicks for heating and cooking stoves." The wick of my prior application and of the present application is made up of a plurality of sheets 30 of non-combustible material separated by a sheet or body of carbonized combustible material. After much experience resulting from the manufacture and use of these wicks, I have found that the best results can be obtained by using inner and outer sheets or 35 layers of asbestos, as the non-combustible material, and by the use of a thick interposed sheet or body of cotton cloth or wick- 40 ing, as the combustible material, which latter has been thoroughly saturated with a liquid containing finely divided mineral or non-combustible material, and has then been carbonized.

I will first describe the wick in its most 45 approved commercial form and will, there- after, consider the same from its broader or more generic aspects.

In the drawings which illustrate the said 50 wick, like characters indicate like parts throughout the several views.

Referring to the drawings: Figure 1 is a 55 plan view of the wick; Fig. 2 shows the wick partly in elevation and partly in vertical section, but with the inner asbestos or non-combustible sheet not yet applied; Fig. 3 is a vertical section taken through the com-

pleted wick on the line x^3-x^3 of Fig. 1; and Figs. 4, 5 and 6 are plan views showing the three elements that make up the preferred form of the wick proper.

The numeral 1 indicates a heavy cotton tube or cylindrical sheet which is preferably a heavy woven cotton fabric known as "wicking," and which, when carbonized, affords the carbonized combustible material of 60 the wick. The numerals 2 and 3 indicate, respectively, the outer and inner asbestos or non-combustible sheets of the wick, and which, primarily, are flat sheets adapted to be bent into cylindrical form.

The wick, as is customary, will be held within a perforated sheet metal cylinder or carrier 4, which has inwardly and upwardly bent clenching lips 5. In the preferred process of manufacture of the wick, the combustible sheet or tube 1 is telescoped within the carrier 4 and its lips 5 are bent upward against the lower end thereof, as shown by full lines in Fig. 2. The wick is then soaked for about twenty-four hours, more or less, in 65 a solution that contains finely divided mineral, such as silica, salt, borax, sodium, alum, copper, ammonia, soluble glass, or potassium.

The wick body 1 is preferably then turned 70 inside out, as shown by dotted lines in Fig. 2, and the outside asbestos sheet 2, being first bent into cylindrical form, is inserted directly inside of the carrier 4, and then the 75 said wick body 1 is turned back into position 80 within the said outer sheet. Then the lips 5 are slightly bent inward and the inside asbestos sheet 3, after being first bent into cylindrical form, is telescoped into the wick body 1, and its lower edge inserted between 85 the same and the upper edges of the lips 5. Said lips are then pressed back against the 90 said inner sheet. The wick thus assembled 95 is then preferably dipped, bodily, into the mineral containing solution, or, as an alter- 10 native, a baking varnish or enamel may be applied to the non-combustible sheets 2 and 3. The wick is then put into a mold and subjected to great pressure and thereby 11 pressed to the right size and to very compact 10 form. Next, the wick is put into an oven and subjected to sufficient heat to carbonize

most of the combustible material. Then the wick is taken from the oven and preferably saturated with kerosene and ignited, and the combustion that then takes place will complete the carbonization of the combustible 11

material and causes a thorough shrinking of the wick. The above noted two-step application of heat has been found to give the best results, but the proper carbonization 5 may be produced in any suitable way.

When the wick is cooled, it is polished both on its exterior and interior, preferably by a steel brush rotating at high speed; and then its upper edge is trimmed, preferably 10 by the use of an emery wheel.

In the completed wick, it will be noted that the non-combustible outer and inner sheets terminate considerably short of the lower edge of the interposed carbonized 15 combustible sheet or body, thus leaving the lower portion of the latter so exposed that it has a good chance to take up the oil by capillary attraction.

When one, or more than one, sheet or 20 layer of carbonized combustible material is used, it is of the greatest importance that they be saturated with the liquid containing, in solution, a finely divided mineral, which, by the liquid, is carried and deposited throughout, the fabric or combustible body. Before carbonization, the liquid which serves as a carrier for depositing the mineral substance throughout the combustible material, must, of course, be dried out, 25 but this drying might be produced as an initial step in the application of the heat for producing the carbonization. The deposited mineral is, of course, a non-combustible material, and hence, remains evenly distributed 30 throughout the combustible material and remaining in the carbonized sheet performing several important functions, to-wit: it increases the strength and solidity of the carbonized material; it gives better porosity 35 thereto, increasing the capillary attraction of the wick; and, to a considerable extent, prevents shrinking of the combustible material during carbonization, and, in a sense, takes the place of substances removed from 40 the wick in the carbonizing action. The treatment above described, without a finely divided mineral deposit, would leave the carbonized combustible material with hollow spaces or gaps that would greatly decrease 45 the capillary oil conducting capacity of the wick, and such carbonized sheet or body would have little or no cohesive 50 strength.

When used in a stove, for example, carbon

deposits will, in course of time, be formed 55 on the upper edge of the wick, but these may be readily removed by turning the wick so that it is even with the top of the metal wick tube (not shown) and then removing the carbon by a gentle use of emery paper. In 60 this way, the wick is not ground down, but is simply left with a clean smooth upper edge surface which gives off a perfectly smokeless blue flame. If, in time, the wick becomes clogged, to a certain extent, with 65 gummy substances left as deposits from the kerosene, the wick need not be thrown away but can be restored to good condition by removing it from the stove, saturating it with oil and then burning the oil therefrom 70 in the open air, which treatment burns out the said gummy deposits and leaves the wick as good as new.

What I claim is:

1. A wick made up of inner and outer 75 cylindrical sheets of non-combustible material and a relatively thick porous sheet of combustible wicking interposed between said inner and outer sheets, said wicking being evenly carbonized throughout and 80 having finely divided mineral evenly distributed therethrough.

2. A wick made up of inner and outer cylindrical sheets of asbestos and a relatively thick porous interposed fabric body 85 of cotton wicking, the latter being carbonized and projecting at its lower edge below the lower edges of said asbestos sheets, and a perforated cylindrical metal carrier surrounding said wick and having an inturned 90 lower edge portion that embraces the depending portion of said interposed wicking.

3. A wick made up of inner and outer cylindrical sheets of asbestos and a thick porous interposed fabric body of cotton 95 wicking the latter being carbonized, and projecting at its lower edge below the lower edges of said inner and outer asbestos sheets, and a perforated cylindrical metal carrier surrounding said wick and having inwardly 100 and upwardly bent clenching lips securely connecting the same at their lower edges.

In testimony whereof I affix my signature in presence of two witnesses.

THOMAS W. GLINES.
